[57] CLAIM

We claim the ornamental design for a laparoscopic surgery tray, as shown and described.

DESCRIPTION

FIG. 1 is a perspective view of the surgery tray of the present invention;

FIG. 2 is a top plan view of the surgery tray;

FIG. 3 is a side elevation view of the surgery tray, with the opposite side having the same design;

FIG. 4 is an end elevation view of the tray from one end, with the opposite end having the same design; and,

FIG. 5 is a sectional view taken along lines 5—5 of FIG. 2. The bottom surface of the surgery tray forms no part of the claimed design.
